[57] ABSTRACT

A composite slide rule showing for different type breadths defining the number of characters in a printed line the number of characters printed for various numbers of lines printed with such types. Advantageously, there is provided an elongated casing with a plurality of parallel channels the cross-section of which is preferably in the shape of a regular polygon such as an equilateral triangle, these channels slidably housing prismatic slides of a corresponding cross-section, the sides of which carry each along its opposite edges cooperating scales of character and line numbers for a predetermined type breadth. This allows reading, through gates extending through the casing, the corresponding character and line figures for the selected character breadth.

COMPOSITE SLIDE RULE

The present invention has for its object a composite slide rule providing a particular means for selecting the standard type, that is the breadth of the type to be used, taking into account the number of signs to be printed and the number of lines available when making up and imposing any matter to be printed.

This improved slide rule also affords means for reckoning, starting from a known number of characters and spacings in a text, the number of lines which is to make up said text, taking into account the relative breadth of type used, that is the actually available number of characters per line for a given breadth of column.

In the case of an already cast off text, in other words when the number of characters in a text and the number of available lines are known, the improved slide rule allows furthermore a suitable breadth of type to be selected.

According to the invention, the slide rule includes a set of scale carrying members or slides corresponding each to different breadths of printing types, the scales on each of said members showing for the corresponding breadth the number of types to be used for different numbers of printed lines.

The accompanying drawings illustrate diagrammatically and by way of example an embodiment of the slide rule according to the invention.

In said drawings:

FIGS. 1 and 2 are general perspective views of the slide rule as seen from above and from below respectively.

FIG. 3 is a perspective view of a detail showing one of the slides of the slide rule according to FIG. 1.

FIG. 4 shows on a larger scale a fraction of one surface of said slide.

The slide rule illustrated includes a set of slides 1 the cross-section of which is in the shape of an equilateral triangle, said slides sliding in parallel guideways formed in a casing 2 having a trapezoidal cross-section.

Said casing 2 is provided with five longitudinal guideways or channels 3 to 7, the cross-sections of said channels being in the shape of equilateral triangles so as to slidably house the corresponding slides 1.

Each of the three longitudinal sides of each slide 1 carries along each of its longitudinal edges a scale, the scale formed along the edge shown at 8 to the left in FIG. 4 is a scale of numbers of lines whereas the scale along the edge shown at 9 to the right in FIG. 4 is a scale of the numbers of types included in the lines the number of which appears in registry with the number of types considered on the opposite edge of the slide side. The number of types obviously depends on the breadth of the type considered, the number of types per line being recorded at the end of the slide side 10 along the transverse edge thereof.

Thus a line of types of a breadth No. 85 includes 85 types as shown in FIG. 4; five lines include 425 types, ten lines 850 types, and so on.

The casing 2 is provided in the section 11 of its outer surface defined by the smaller base of its trapezium-shaped outline (FIG. 1) with two gates 12, 13 opening respectively into the channels 4 and 6. Similarly, in the section 14 of the outer surface of the casing defined by the larger base of its trapezium-shaped outline (FIG. 3), there are provided three gates 15, 16, 17 opening respectively into the channels 7, 5 and 3.

Thus assuming 79 lines are available for printing a text of 6,000 signs and spacings, it is possible to ascertain the breadth of type best suitable for this purpose; to this end, that slide is selected which carries on its scale of types and in registry with the number of lines 79, a number of types equal to or above 6,000. The slide thus selected is introduced into the channel 6, for instance, of the casing 2 with the side corresponding to the breadth of the type considered, the breadth 76 in this example, facing the section 11 of the surface of the case 2. The slide 1 is pushed inside the channel 6 until the number of lines 79 appears to view through the gate 13 and it is thus possible to read, in registry with said number of lines 79, the corresponding number of types, to wit 6,004.

Assuming it is desired to print a text including 5,800 signs and spacings with types of a breadth standard No. 85, it is possible to define the number of lines required as follows: there is introduced into the channel 6, for instance, of the casing 2, a slide 1, one of the sides of which carries the scales for a breadth of type No. 85. This side should face the section 11 of the casing surface, so that the slide 1 may be shifted inside the channel 6 until the number of types 5,865 appears to view through the gate 13. In registry with said number of types, the total number of lines required may then be read, to wit 69 lines.

Now, assuming it is desired to ascertain the number of signs and spacings forming a text to be printed, with types of a breadth No. 90, on 72 lines, for instance, there should be introduced into the channel 6, for instance, of the casing 2 that slide which carries on one of its sides the scales provided for said types of a breadth No. 90. Said side should face the section 11 of the outer surface of the casing 2, the selected slide being shifted inside the channel 6 until the number 72 on the scale of lines appears to view through the gate 13. In registry with said figure 72, the number of signs and spacings, in the present case 6,480, will be read as the number of types which can be printed on 72 lines with said types of a breadth No. 90.

The gates 12, 13 and 15-17 formed in the outer surface of the casing 2 serve, on the one hand, for ascertaining the number of types of a given breadth which corresponds to a predetermined number of lines and, on the other hand, for comparing the data given out by slides corresponding to different type breadths.

Numerous modifications may be brought to the embodiment described hereinabove without widening the scope of the invention, as defined in the accompanying claims.

Thus, the cross-section of the slides may be chosen as desired, say square or hexagonal for instance, so as to show thus four or six sides carrying scales corresponding to different breadths of type. Of course, the channels in the casing 2 should then be given a corresponding polygonal cross-section.

Such polygonal slides may be hollow or solid. A hollow slide the cross-section of which is in the shape of an equilateral triangle, for instance, may be obtained for instance through the mere folding of a sheet of cardboard, plastics or metal, which has been longitudinally printed and corrugated. It is thus possible to supply the slides in a flat condition.

Flat slides may also be provided so as to be slidably fitted in slideways or channels of a corresponding shape, similar to those of a conventional slide rule. In

such a case, the marking may be executed along the very edge of the slides or again by means of an advantageously transparent slider, of the kind used in conventional slide rules.

I claim:

1. A composite slide rule for providing the relationship between the breadth of a particular size of type to be used, the number of characters to be printed and the number of lines to be printed with said type comprising, an opaque casing trapezoidal in cross section and provided with five parallel longitudinal channels, said channels each having the shape of an equilateral triangle, the base of one channel adjoining an apex of an adjacent channel, a pair of viewing openings in one paral-

lel side of said casing and three viewing openings in the opposite parallel side of said casing, a prismatic equilateral shaped scale carrying slide disposed in each of said channels, each side of each of said slides bearing indicia relating to a number of lines and a corresponding number of characters, each end of each said slide bearing indicia indicating a breadth of type relating to that particular side whereby reciprocating a selected slide in its related channel provides the user with the number of type characters and spaces relative to the number of lines available for printing when the selected number of lines appears in the related viewing opening.
